AUGUSTE MAGIS AND ANDRÉ HUET, OF PARIS, FRANCE, ASSIGNEES TO THE SUPER-
HEATER COMPANY, OF NEW YORK, N. Y.

BOILER

Application filed February 7, 1929, Serial No. 338,145, and in France February 18, 1928.

Little effort has been made so far in steam plants and particularly in movable plants to condense the exhaust steam by a complete recuperation system in order to obtain the best possible economy and also to close the circuit in order to minimize the necessary quantity of make-up fluid.

The present invention has for its object the provision of a generator, making it possible to obtain a better production and utilization of steam or any other fluid and to combine the use of high pressures and high superheats with as great a recuperation as possible.

This generator is more particularly applicable to movable installations such as locomotives, locomobiles, automobiles, etc., and comprises a certain number of boilers or re-heaters heated by heat exchangers working on a closed cycle and arranged consecutively in the path of the hot gases coming from the furnace. This arrangement presents the following essential feature that the boilers are connected to each other on the one hand at their lower points to permit the circulation of the feed water which is introduced into the coolest boiler according to the counter-current principle, and on the other hand at their higher points to equalize the steam pressures existing in the boilers.

The steam is taken off above the water level of the hottest boiler to be taken into a superheater and thence to the prime mover which may be of the multiple expansion type and whose cylinders of different pressure stages are thus arranged in series.

This disposition is the reverse of that existing in multiple expansion engines used hitherto in combination with a generator comprising several boilers, since in these former cases the boilers are connected respectively to cylinders of different pressure stages. Complications of distribution and coupling inherent in the separation of the boilers and cylinders are thus avoided.

Moreover, it is thus possible to arrange between two successive stages a receiver for intermediate reheating of the steam coming from its work in one of the stages and going to a further stage, by means of steam that

has been superheated and comes directly from the superheater placed at the exit of the hottest boiler or by means of saturated steam coming directly from the hottest boiler.

Finally in the generator forming the subject of the present invention an attempt has been made to obtain the greatest possible heat recuperation, and it is for this reason that the steam after having done its work in the several stages is in part condensed in a preheater for air introduced into the furnace and in part in a water preheater to return finally to the coolest boiler with the feed water.

The following description to be read in connection with the accompanying drawing and given by way of illustration will make it clear how this invention can be carried out.

The single figure of the drawing represents diagrammatically in longitudinal section a steam generator according to the principles just stated.

In this figure, *g* designates the grate on which the combustible is burned and the gases of combustion flow as indicated by the arrow *f1* passing over a first heat interchanger *e1* where the water, for example, is vaporized. This water will be condensed in the exchanger *e2* located in the boiler *t1* and in condensing it vaporizes the water contained in the boiler and thus produces steam at a high pressure.

The gases continuing their travel next pass over the superheater *s* where they raise the temperature of the steam coming from the high pressure boiler *t1* to a predetermined temperature. Continuing their travel these gases then flow over the exchanger *e3* where they are completely cooled, vaporizing the water contained in this bundle.

The steam coming from the bundle *e3* travels into the heat exchanger *e4* located in the boiler *T2* and is there condensed while heating or vaporizing the water of this boiler.

This heated water can travel by the tubes *e2* into the boiler *t1* where it is completely evaporated.

It is evident that there might be several boilers and several closed circuit heat interchangers working either at the same pressure

as in the example given or at different pressures in parallel series corresponding to special engines or for other purposes (generating power, heating or other purposes).

5 In the form of the invention shown in the drawing, the two boilers t_1 , t_2 communicate at their upper parts by the tube c_1 and thus work at the same steam pressure just as at the lower part they are connected by a tube 10 c_2 which permits the feed water introduced into the boiler t_2 to pass from that boiler into the boiler t_1 in response to the level difference resulting from the different rates of vaporization.

15 The steam produced in these boilers and superheated in the superheater s is carried by the tube c_3 to the high pressure engine m_1 where it expands up to its saturation point doing a certain amount of work.

20 The exhaust steam coming from the engine m_1 is then carried by the pipe c_4 to a reheater r where its temperature is raised under the same pressure by means of a part of high pressure steam taken, for example, from the 25 pipe c_3 and conducted by the pipe c_5 into the exchanger e_5 of the reheater where it is condensed, returning by the tubes c_6 to the boiler t_1 while still at a high temperature and practically under the pressure of boiler t_1 . The 30 steam used for reheating may thus be advantageously circulated by a thermo-siphon effect through the interior of these exchangers.

From the exit from the reheater r the steam 35 travels by the pipe c_7 to an engine m_2 working at a lower pressure where it expands further.

From the outlet of the engine m_2 a part of 40 this steam may be used to generate the draft for the boiler going to the stack h for this purpose through the pipe c_8 , the other part flowing by means of the pipe c_9 to a preheater a for the combustion air, in which the air entering at the front and following the arrow 45 f_2 is forced, for instance by the speed of the locomotive, under the grate g through a duct b , while the exhaust steam coming from the pipe c_9 is cooled in the coil e_6 and leaves by the pipe c_{10} .

50 This air preheater may advantageously be combined with an air preheater heated by waste gases and in that case would be placed in front of the stack h so that the air would be first heated by steam and then by the hot 55 gases.

The steam then flows to a feed water pre-heater where it gives up part of its heat to the water contained in the preheater d by means of the coil 7 .

60 The resulting water next has its oil separated out by means of the separator i and is then delivered into the chamber k which receives water coming from the tender by the tube c_{11} after it has been heated in the pre-

heater d whence it flows to the chamber k through the pipe c_{12} .

This water is then forced by the pump p into the boiler t_2 where it may be again heated and vaporized.

At ratings of the locomotive at which the boiler t_2 evaporates water, the two boilers t_1 and t_2 might be arranged as a single boiler communicating at their lower parts so that the hot water from t_2 might travel into t_1 where it would be vaporized, these two boilers also being in communication at their upper points so that the steam from t_2 might also flow to the engines.

It is quite evident that without passing outside of the frame of this invention one could provide a plurality of successive expansions in different engines arranging several intermediate reheaters to improve the economy. Similarly, steam conducted by the pipe 7 to the exhaust might be utilized in a low pressure motor to drive a fan furnishing the draft, this fan being driven when the locomotive stops by steam taken directly from the boiler.

We claim:

In apparatus of the class described, the combination of a plurality of boiler sections each having its own internal thermal circulation independent of the remainder; a heat transferring appliance associated with each section comprising a heat-absorbing element below the section, a heat-delivering element in the section, portions connecting the two elements, each appliance forming a closed circuit, and a fluid in each appliance; a furnace whose products of combustion touch the several heat-absorbing elements in succession; the several sections being aligned horizontally; means placing the sections into communication both above and below the level at which water is to be maintained; an inlet to supply water to the section farthest from the furnace; a steam outlet from the section nearest to the furnace, whereby the several sections can be maintained at the same pressure but different temperatures.
